UNITED STATES PATENT OFFICE.

WILLIAM T. PRATER, OF BLOOMFIELD, MISSOURI.

SAFETY-STIRRUP.

1,124,801.

Specification of Letters Patent. Patented Jan. 12, 1915.

Application filed April 14, 1914. Serial No. 831,784.

To all whom it may concern:

Be it known that I, WILLIAM T. PRATER, a citizen of the United States, residing at Bloomfield, in the county of Stoddard and State of Missouri, have invented new and useful Improvements in Safety-Stirrups, of which the following is a specification.

The primary object of the invention is the provision of a safety stirrup wherein the construction thereof enables the quick release of the foot of a horseback rider therefrom should the animal become fractious or fall, thereby avoiding the possibility of either foot being hung or held fast in the stirrup, which would result in preventing such rider from becoming liberated to obviate injury during a hazardous moment.

Another object of the invention is the provision of a safety stirrup wherein the tread bar will be automatically released under the action of the foot of the rider, that is to say, should the foot rock or become lifted in the stirrup, and in this manner the foot will be freed, thus obviating the accidental throwing of such rider from his mount on the saddle in event the animal becomes frightened or falls.

A further object of the invention is the provision of a stirrup wherein the safety latch can be adjusted to accommodate different sizes of feet in the stirrup for the convenience of the rider.

A still further object of the invention is the provision of a safety stirrup of this character which is simple in construction, serviceable, positive and reliable in its operation, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing:—Figure 1 is a perspective view of a stirrup constructed in accordance with the invention ready for use. Fig. 2 is a similar view showing the foot bar released. Fig. 3 is a vertical longitudinal sectional view through the stirrup when ready for use. Fig. 4 is a sectional view on the line 4—4 of Fig. 1. Fig. 5 is a fragmentary vertical sectional view through the adjustable clip. Fig. 6 is a sectional view on the line 6—6 of Fig. 5.

55 Similar reference characters indicate cor-

responding parts throughout the several views in the drawing.

Referring to the drawing in detail, the stirrup comprises a frame 10 of substantially inverted U-shape, including spaced 60 depending inner and outer side limbs 11 and 12 respectively, the frame being provided with a suitable slotted ear 13 at the center thereof for receiving the stirrup strap for connecting the stirrup to a riding saddle. 65 It is of course to be understood that the frame 10 is preferably made from metal, although it may be made from any other suitable material possessing the requisite strength and durability. The inner side 70 limb 11 of the frame is extended beyond the outer side limb 12 and has at its free end a split bearing 14 between which is arranged one end of a cross tread bar 15, the end engaged between the bearing 14 being 75 swingingly supported upon a pivot 16 mounted in the said bearing 14, while the limb 12 is slotted to form a loop 17 in which is received an upturned latch end 18 formed at the opposite extremity of the tread bar 80 15, the said latch end 18 being provided with an offset portion forming a shoulder 19 which engages the lower end of the loop 17 to hold the tread bar 15 in position for closing the stirrup and to support the foot 85 of the rider when engaged therein.

Slidably fitted on the inner side limb 11 of the frame is a clip 20 having a slot 21 for receiving any one of a series of lugs 22 formed on the limb 11 so as to hold the clip 90 20 in vertical adjusted position thereon, the clip at the portion embracing the side limb 11 being formed in one side thereof with an internal groove 23 which permits the clip 20 to pass the lugs 22 on the limb 11 when the said clip is rotated thereon to bring the groove 23 in alinement with the lugs, and in this manner the clip can be readily adjusted. Swingingly connected to the clip 20 by means of a pivot is a trip latch, hereinafter fully described.

Fitted on the inner stretch of the loop 17 of the outer limb 12 of the frame is a releasing slide member 25 bent into substantially figure 3 shape, having in one end a 105 seat 26 to receive the latch end 18 on the tread bar, while bearing against the opposite end is a coiled expansion spring 27 which surrounds the outer side limb 12 and has its opposite end working against a col- 110

lar 28 secured to the side limb 12 so as to sustain the frame under tension to normally hold the slide member 25 in position for locking the tread bar closed. This slide member 25 is designed for rotation on the outer side limb 12 as well as for sliding movement thereon, and is adapted to co-operate with the latch presently described.

The latch comprises a channeled arm 29 which is pivoted to the clip 20 and in the channel of this arm is adapted to engage a second arm 30, the same being supported upon a pivot fixed in the arm 29, and is engageable at its free end in a seat 32 formed between the curved ends of the slide member 25 when the arm 30 rests in the channeled portion of the arm 29 to prevent the turning of the slide member 25, and thereby releasing the tread bar. The arm 29 is formed with an extension 33 with which is adapted to engage the foot of a rider so as to move the arm 29 outwardly away from the arm 30, thereby disengaging the latter from the seat 32, which frees the sliding member 25 for rotary movement, and on the rotating thereof by any downward pressure upon the tread bar 15, will disengage the latch end 18 of the latter from the loop 17, thus the tread bar 15 will swing to open position and free the foot from the stirrup. Should the check bar 15 be in normal closed position and the foot of a rider resting thereon, now when the foot is raised in the stirrup the same will be brought into contact with the arms 29 and 30 which are in position for locking the member 25 against rotation, and on the outward pressure of the foot against the arm the member 25 will be slidably raised on the inner stretch of the loop 17 of the frame 10, thus disengaging the latch end 18 of the tread bar and thereby unlocking the same to permit the freeing of the foot from the stirrup. It will be apparent that the tread bar 15 will be unlocked should the foot of the rider rock in

the stirrup or be lifted thereon so that the foot will be readily freed or disengaged from the stirrup in event of the animal becoming fractious or falling. The dragging of the rider will be prevented when the stirrup is in use, and the possibility of the hanging of the foot therein is obviated, so that the user of the stirrup is insured against injury while in active riding.

From the foregoing it is thought that the construction and manner of operation of the device will be clearly understood, and therefore a more extended explanation has been omitted.

What is claimed is:—

1. A safety stirrup comprising a frame having spaced side limbs, a tread bar hinged to one of the limbs, a loop formed on the other limb, a latch end on the tread bar and engageable in the loop, a releasable slide mounted on one stretch of the loop and engaging the latch end of the tread bar, and trip means adjustably connected to the other side limb and engaged with the releasing slide to hold the same in locking position. 70

2. A safety stirrup comprising a frame having spaced side limbs, a tread bar hinged to one of the limbs, a loop formed on the other limb, a latch end on the tread bar and engageable in the loop, a releasable slide 75 mounted on one stretch of the loop and engaging the latch end of the tread bar, trip means adjustably connected to the other side limb and engaged with the releasing slide to hold the same in locking position, 80 and means operative upon the slide to normally hold the same in position for engagement with the latch end of the tread bar.

In testimony whereof I affix my signature in presence of two witnesses.

WILLIAM T. PRATER.
